MEANS FOR CLEANING WELL SCREENS

John M. Reynolds, Shreveport, La., assignor to
Orpha E. Reynolds, Shreveport, La.

Application September 22, 1941, Serial No. 411,810

2 Claims. (Cl. 166—20)

This invention relates to means for cleaning well screens.

An object of the invention is to provide a novel means for cleaning well screens while located in the well.

Another object of the invention is to provide means for alternately removing liquid from within a well screen and then introducing liquid into the well screen to thereby vary the pressure acting on the screen to dislodge particles in the screening portions of the well screen.

Another object of the invention is to provide means for cleaning a well screen suspended in a well bore by a tubing which comprises a tubular member insertable into the tubing, a pump at the lower end of the tubular member, a packer at the lower end of the tubular member to form a seal between the tubular member and the screen, the pump having an outlet through the tubular member above the seal whereby fluid may be removed from within the screen and tubular member by the pump, and then fluid may be introduced into the screen under pressure by means of the tubular member.

The invention may also be used for acidizing as well as for cleaning a well.

With the above and other objects in view the invention has particular relation to certain novel features of construction, operation and arrangement of parts, an example of which is given in this specification and illustrated in the accompanying drawing, wherein:

Figure 1 shows a longitudinal sectional view of the pump used in the apparatus.

Figure 2 shows a transverse sectional view taken on the line 2—2 of Figure 4.

Figure 3 shows a transverse sectional view taken on the line 3—3 of Figure 1.

Figure 4 shows a longitudinal sectional view of the apparatus inserted in a well screen, and

Figure 5 shows another embodiment of the type of pump, or bailer, employed.

Referring now more particularly to the drawing wherein like numerals of reference designate similar parts in each of the figures, the numeral 1 designates a well tubing to the lower end of which is connected a conventional well screen 2, which has narrow slits 3 through which liquid may enter into the well screen. The lower end of the well screen is closed by a threaded plug 4. When the slits 3, 3 of the screen 2 become clogged with sand and dirt, no liquid can flow out of the well bore into the screen and also no liquid can flow into the well bore from the screen. The screen and tubing form no part of the invention and are merely shown to explain the use of the invention.

Within the tubing 1 is a pipe 5 which is insertable downwardly into the tubing and withdrawable upwardly therefrom. At the lower end

of the pipe 5 is a packer which comprises the resilient sleeve 6 which is held on the pipe 5 by means of supporting rings 7, 7, the packer forming a seal between the tubing adjacent the screen and the pipe 5. Different types of packers may be used depending upon the construction of the screen. Within the lower end of the pipe 5 are the supporting wings 8, 8 which support the pump barrel 9 within the pipe 5.

The pump, a form of which is clearly illustrated in Figure 1, comprises the tubular barrel 9 which is closed at its lower end by the flap valve 10 which opens upwardly to allow entrance of fluid into the barrel. The lower end of the barrel also has a side opening 11 which is closed by the semi-cylindrical sleeve 11a rotatably mounted on the barrel. This side opening is provided to allow sand in the barrel to be readily removed to clean the pump after use.

The upper end of the barrel 9 is closed by a head 12, which is threaded into said barrel. This head has a central axial bore 9a which is reduced in diameter at the upper end of the head as at 12a and outwardly flared at the lower end to form the tapered seat 13. The upper end of the head has a gland 14 attached thereto. The head has a lateral threaded hole 15 therethrough communicating with the central bore 9a. A short tubular nipple 16 is threaded into said hole 15 in the head and extends through the pipe 5 in sealing relation therewith. A check valve 17 in the conduit of the nipple 16 is effective to prevent flow of fluid from outside of the pipe 5 into the head 12 through said conduit but to allow outflow of liquid.

A piston rod 18 is reciprocable through the gland 14 and head 12, and terminates at the upper end in an enlarged pointed knob 19. A cable with a conventional grappling tool on the end thereof, not shown, may be lowered through the pipe 5 to land on the pointed knob 19, engaging therewith to reciprocate the piston rod 18. The lower end of the piston rod 18 is enlarged to form a cap 21 and flares downwardly from the rod at 20, being shaped to cooperate with and fit closely against the tapered seat 13 in the head 12 to close the upper end of the barrel. The cap 21 is smaller in diameter than the inside diameter of the barrel 9 and has a central hole 22 therein, with lateral ports 23, 23 from the hole 22 through the cap. Threaded into the hole 22 is a tubular piston mandrel 24 which has a tapered seat at the upper end thereof, and a valve 26 is reciprocable in the hole 22 and arranged to cooperate with said seat 25. Loosely mounted on the piston mandrel 24 are the rigid piston rings 27, 27, 27 whose outside diameters are smaller than the inside diameter of the barrel 9 so that a substantial clearance is provided between the piston rings and the barrel 9 to reduce the wear

caused by sand and grit in the fluid being pumped. In the embodiment illustrated in Figure 5, the upper tapered end of the cap 21 is provided with grooves 28 forming liquid passageways and secured to said cap, beneath the lower ends of said grooves, and extending outwardly beyond the cap there is a flexible annular fin 21a, forming a fin valve. In this type of the pump, upon movement of the piston upwardly, should the pressure in the barrel 9 be greater than the pressure outside thereof, the liquid under pressure in the barrel can escape past the fin valve 21a and out past the back pressure valve 17; but when the piston reaches its upper position, as shown in Figure 5, the velocity of the liquid under pressure passing through the grooves 28 will be sufficiently high to force the margin of the fin valve 21a against the lower end of the head 12 thus closing said passageways 28 and retaining the pressure in the barrel 9a.

Under certain conditions when the pump is removed from the well it is desirable that pressure be retained within the pump barrel 9 so that when the pump reaches the ground surface, the sleeve valve 11a may be opened and the contents of the barrel 9 will be discharged by the pressure retained therein.

The tubing 1 and the pipe 5 extend to the ground surface and are supported by a suitable tubing head having conventional valves and fittings (not shown) so that liquid may be selectively admitted to either the pipe or tubing, or outside of the tubing between the casing or well walls and tubing.

After the screen 2 has remained in the well for a considerable period of time, the slits will become clogged so tightly with grit and sand that no fluid will pass from outside of the screen to the interior thereof. In order to clean the screen without removing the same from the well bore, this novel apparatus and method can be used. The pipe 5 is lowered into the well with the pump located therein and a seal is formed between the lower end of the pipe and the screen 2 or tubing 1 supporting the screen by means of the packer. There is usually a considerable amount of liquid in the well bore inside of the screen and tubing 1 and outside the screen so that there is a high hydrostatic pressure within the well bore and screen. The liquid in the producing formation is also usually under high pressure. The liquid is then removed from within the screen and pipe by reciprocation of the piston in the pump. More particularly, a cable with a grappling tool is lowered into the pipe 5 which engages the pointed knob 19 so that when the cable is reciprocated, the stem 18 and plunger is reciprocated. In operation, the plunger will drop downwardly by gravity, fluid in the barrel 9 is displaced by the piston, the fluid passes through the tubular mandrel 24 and raises the check valve 26 off of the seat and passes through the ports 23, 23 to thereby allow the plunger to drop, the flap valve 10 meanwhile being closed so that fluid does not escape from the barrel 9. Then as the plunger is raised, the fluid entrapped therein is forced out of the upper portion of the barrel 9 through the axial bore 11 of the head and through the nipple 16 into the space between the pipe 5 and tubing 1; and simultaneously the barrel is filled by liquid entering through the flap valve 10. The check valve 17 in the nipple prevents fluid from entering the head of the barrel so that upon down stroke of the plunger again, the barrel will not

be filled with the discharged liquid. It can therefore be seen that reciprocation of the plunger is effective to pump liquid from the screen into the space between the tubing and the pipe 5 to thereby reduce the hydrostatic pressure within the screen. The formation pressure then acts against the screen tending to force clogging material from the holes 3 inwardly into the screen.

10 The plunger is then held in its uppermost position so that the flared surface of the cap 21 contacts with the tapered seat 13 or the fin-valve 21a co-acts with the lower end of the head 12 to close the upper end of the pump so that no 15 pressure can escape through the pump. Liquid is then delivered into the pipe 5 at the ground surface until there is a large column of liquid standing in the pipe so that there is a high hydrostatic pressure within the screen. It can be noted by an inspection of Figure 2 that there is a passageway between the pump and pipe 5 to allow liquid from within the pipe to pass to the screen. The liquid under hydrostatic pressure in the screen then acts to force the material clogging screen outwardly. The hydrostatic pressure in the screen may be supplemented by pump pressure applied to the tubing at the surface.

The liquid again may be transferred from the screen and pipe, by means of the pump, into the space between the pipe 5 and tubing 1 to again 30 reduce the pressure within the screen. Of course overflow lines are provided at the tubing head to allow liquid between the pipe and tubing to be discharged therefrom. These operations 35 may be continued as long as desired and until the screen clogging material is removed from the screen.

The drawing and description are illustrative merely while the broad principle of the invention 40 will be defined by the appended claims.

What I claim is:

1. A device of the character described for 45 cleaning a screen connected to the lower end of a tubing in a well comprising a pipe in the tubing, a packer on the pipe forming a seal between the pipe and the tubing, a pump in the pipe arranged to remove liquid from within the tubing beneath the packer and discharge it into the tubing exteriorly of the pipe and above the 50 packer to reduce hydrostatic pressure in the screen caused by liquid in the pipe, said pipe having a passage leading from above the pump into the screen beneath the pump and whereby liquid may be introduced from the pipe into the 55 tubing to raise the hydrostatic pressure in the screen.

2. A device of the character described for 60 cleaning a screen connected to the lower end of a tubing in a well comprising a pipe adapted to be lowered into the tubing, a packer on the pipe adapted to form a seal between the pipe and the tubing, a pump in the pipe, there being a passageway leading from the pipe above the pump into the screen beneath the pump, said 65 pump being arranged to remove liquid from within the pipe and screen and discharge it exteriorly of the pipe into the tubing above the packer to reduce hydrostatic pressure in the screen caused by the weight of the liquid in the pipe, and means in the pump movable into active position to prevent outward flow from within the pipe through the pump whereby liquid introduced into the pipe will be retained therein to raise the hydrostatic pressure within the screen.

JOHN M. REYNOLDS.
